UNITED STATES PATENT OFFICE.

HUGH R. ROBINSON, OF BROOKLYN, NEW YORK, ASSIGNOR TO WESTERN ELECTRIC COMPANY, INCORPORATED, OF NEW YORK, N. Y., A CORPORATION OF NEW YORK.

CONTROL OF RELAYS.

Application filed April 21, 1924. Serial No. 707,862.

To all whom it may concern:

Be it known that I, HUGH R. ROBINSON, a citizen of the United States of America, residing at Brooklyn, in the county of Kings 5 and State of New York, have invented certain new and useful Improvements in Control of Relays, of which the following is a full, clear, concise, and exact description.

This invention relates to relaying electrical variations, and aims to improve control of the relaying operation.

A particular object is to stabilize the electrical output characteristics of relay apparatus.

15 For brevity and clearness, the invention is described hereinafter with special reference to its application to electric discharge relay apparatus involving a well-known form of three-electrode tube, although not necessarily limited to apparatus of that type.

Another object of the invention is to reduce the tendency of variations of cathode energizing current to result in undesired electrical variations in the output circuit of 25 the relay.

Another object of the invention is to reduce the tendency which changes in cathode heating current have to vary the voltage bias of the control electrode, or to vary this 30 voltage bias and the voltage applied across the anode and cathode. It is desired to reduce this tendency especially where a plurality of tubes have their cathodes in serial relation.

35 A still further object is to utilize a tube which is subject to filament voltage variations to counteract the tendency that different filament voltage variations of another tube have to cause undesired electrical variations in a circuit connected thereto. It is especially desired to employ this feature of the invention in order to maintain balance and reduce undesired gain variations in a 40 push-pull amplifier having its cathodes connected in series; and also to employ this feature in order to reduce carrier leak in a balanced modulation circuit having its cathodes connected in series.

In the forms of the invention specifically 50 illustrated and described herein, the desired compensation for variations of voltage of the cathode of a tube is obtained by shunting across the source of voltage employed for heating the cathode, a circuit comprising 55 a resistance and a source of potential for biasing the control electrode of the tube,

and connecting the control electrode to the proper point on this resistance, as pointed out hereinafter. Where a plurality of tubes having their cathodes in series, preferably a 60 separate resistance, such as that just referred to, is employed for each of the tubes, and a common source of grid potential may be employed, with the resistances all connected to proper points on the battery, as pointed out hereinafter. In a balanced tube circuit, as for instance in a push-pull amplifier or a balanced modulator, by properly compensating each tube for variations of its voltage, the balance of the circuit is maintained, 65 and undesired gain variations of the circuit are reduced, and, in the case of the modulator, by a maintenance of balance the carrier leak is reduced.

70 Further objects and advantages of the invention will appear from the following description of the drawings, of which Fig. 1 is a diagram for use in explaining certain features of the invention; Fig. 2 is a diagram of a form of the invention embodied 75 in a modulating system for high frequency carrier wave signaling in which the carrier current used for transmission is suppressed except when modulated at low frequency, 80 the modulating device employed being of 85 the thermionic type.

In many of the vacuum tube circuits used at present, any change in the filament voltage and current produces changes in grid bias and applied plate potential which are 90 of such relative values that the plate current changes. For instance, when the biasing battery (or other source of grid potential) and the plate battery (or other source of plate current) are connected to the positive side of the filament, an increase in filament voltage causes a decrease in the plate resistance and an increase in the space current due to two changes: the decrease in the value of applied negative grid potential 95 and the increase in applied plate potential. (The change in electron emission is here neglected since the tubes usually operated in the saturation condition and the effect of change in emission is consequently of little 100 importance.) Furthermore, when filaments of two or more tubes are connected in series and the tubes are supplied from the same sources of grid and plate potential, the effect is greater than when the tubes farther from 105 the common point are supplied from the sources of filament current, plate current,

and grid potential. This is especially disadvantageous in circuits of the balanced type, such as balanced modulators or de-modulators, and push-pull or other balanced 5 amplifiers.

A circuit will now be described which embodies means for either maintaining the grid bias constant or varying it to compensate the changes in plate resistance and 10 applied plate voltage due to variation of filament voltage, regardless of the position of the tube in the circuit.

Referring to Fig. 1, three electron discharge tubes 1, 2, and 3, which may be of 15 the well-known three electrode type comprising anodes, filamentary cathodes, and grids, have their filaments connected in series. These tubes are intended to represent a plurality of tubes connected in any 20 desired input and output circuits. Therefore, and in order to avoid complication in the drawing, the input and output circuits were not shown in Fig. 1. One possible arrangement of input and output circuits for 25 a plurality of such tubes, used in accordance with the invention, will be set forth later in connection with the description of Fig. 2. In Fig. 1, preferably a common plate battery 5 supplies plate current for 30 each of the tubes 1, 2, and 3. A common filament battery 10, having its positive pole connected to the negative pole of the plate battery 5, supplies heating current for the 35 cathodes of tubes 1, 2, and 3, this current flowing from battery 10 through the filament of tube 1, the filament of tube 2, the filament of tube 3 and preferably through a resistance 11 and an adjustable resistance 12, back to the filament battery. The 40 resistance 12 may be used to adjust the filament current, and the resistance 11 may be used to adjust the voltage across battery 10 and resistance 12.

Preferably, a common grid battery 20, 45 having its positive pole connected to the positive pole of the filament battery 10, supplies potentials for the grids of tubes 1, 2, and 3. The grid of tube 1 is connected to the junction point of two resistances, b_1 and d_1 , which are connected in series with each 50 other between a point on the grid battery 20 and the junction of the resistances 11 and 12. Similarly, the grid of tube 2 is connected to the junction of two resistances, b_2 and d_2 , which are connected between another point on the grid battery 20 and the 55 junction of resistances 11 and 12. The dotted portions of the leads between the grids of the tubes and the resistances b_1 , d_1 , the resistances b_2 , d_2 , and the resistances b_3 , d_3 , respectively, are intended to indicate any 60 desired sources of input voltage for the tubes. The resistances b_1 and d_1 , the resistances b_2 and d_2 , and the resistances b_3 , d_3 , are preferably large enough to make 65

no great current drain on the grid battery 20. It will now be explained how the desired compensation for changes of filament current can be made for each tube so that upon variation of the filament current, the 70 resultant change in grid potential will substantially neutralize the effect, upon the plate current, of the resultant change in the applied voltage across the anode and cathode; or, if desired, so that the grid potential remains constant upon variation of the 75 filament current.

Let G designate the negative potential desired on the grid of any given one of the tubes. (Thus G_2 , on the drawing indicates the potential difference between the grid and the midpoint of the filament of tube 2, the subscript of G indicating the particular tube involved. Where no subscript is employed, the designations apply to the resistances, voltages, etc. for any given one of the tubes.)

Let C designate the negative potential which is necessary to obtain from the grid battery 20, the grid of the given tube. (For 90 instance, C_2 , in Fig. 1, designates the corresponding potential difference across the part of the grid battery 20 employed to supply biasing potential for the grid of tube 2.)

Let A designate the voltage drop across 95 battery 10 and resistance 12, as indicated in Fig. 1. Let the voltage drop in the filament of the given tube be designated by F , as indicated by the drops at F_1 , F_2 , and F_3 in Fig. 1.

Let K designate the ratio of the voltage drop between the electrical midpoint of the filament and ground. (Positive pole of filament battery to the total voltage drop (A) in the filament circuit. Thus $K_2 \times A$, in 105 Fig. 1, designates the voltage between the positive end of battery 10 and the electrical midpoint of the filament of tube 2.)

Let M designate the voltage amplification constant of the tube.

The formulae for obtaining the desired compensation, to maintain constant plate current under variations of filament current, will now be stated, and the derivation will be given. These formulae are based on 115 the supposition that the grids never become positive with respect to the filament, and K is a constant, and that no allowance is to be made for changes of electron emission from the filament. The formulae are: 120

$$\frac{b}{d} = \frac{K + \frac{K}{M}}{1 - K - \frac{K}{M}}$$

$$C = \frac{G - \frac{KA}{M}}{1 - K - \frac{K}{M}}$$

125

130

The derivation of the formulæ follows:

$$G = A(1 - K) + V_d V_d + V_b = C - A$$

where V_d and V_b are the voltage drops in the resistance d and b .

$$V_d = \frac{d}{d+b} (V_d + V_b)$$

$$= \frac{d}{d+b} (C - A)$$

$$G = A(1 - K) + \frac{d}{d+b} (C - A) \quad (1)$$

$$= A\left(1 - K - \frac{d}{d+b}\right) + \frac{Cd}{d+b}$$

For every change in $A, \Delta A$, there is a change in $G, \Delta G$. The change in plate potential is $K \Delta A$ and the compensating 20 changer in G is $\frac{K \Delta A}{M}$.

$$\therefore \Delta G = \frac{K}{M} \Delta A. \quad (2)$$

$$G = \frac{K}{M} + \text{a constant.}$$

From equations (1) and (2)

$$1 - K - \frac{d}{d+b} = \frac{K}{M}$$

$$d + b - Kd - Kb - d = \frac{Kd}{M} + \frac{Kb}{M}$$

$$b - Kb - \frac{Kb}{M} = Kd + \frac{Kd}{M}$$

$$\frac{b}{d} = \frac{K}{M} + \frac{K}{1 - K - \frac{K}{M}}$$

$$C = KA + G + V_b$$

$$V_d = G - (1 - K) A$$

$$V_b = \frac{b}{d} \quad V_d = \frac{K + \frac{K}{M}}{1 - K - \frac{K}{M}} (G - A + KA)$$

$$C = KA + G + \frac{(G - A + KA) \left(\frac{K}{M} + \frac{K}{1 - K - \frac{K}{M}} \right)}{1 - K - \frac{K}{M}}$$

$$KA - K^2 A - \frac{K^2 A}{M} + G - GK - \frac{GK}{M} +$$

$$GK + \frac{GK}{M} - KA - \frac{KA}{M} + K^2 A + \frac{K^2 A}{M}$$

$$1 - K - \frac{K}{M}$$

$$C = G - \frac{KA}{M}$$

$$1 - K - \frac{K}{M}$$

When it is desired to maintain a constant grid bias, M may be considered infinite, (the condition to make an infinitely small change in grid potential compensates for any finite change in applied plate potential), and the formulæ become:

$$\frac{b}{d} = \frac{K}{1 - K}$$

and

$$C = \frac{G}{1 - K}$$

Fig. 2 illustrates an application of the invention to a modulator of the general type disclosed in Fig. 4 of J. R. Carson Patent 1,343,306, June 15, 1920. In Fig. 2, tubes 1, 2, and 3 correspond to the tubes 1, 2, and 3 respectively of Fig. 1. Similarly, plate battery 5, filament battery 10 and grid battery 20, of Fig. 2 correspond to the batteries 1, 10, and 20 of Fig. 1. Also, resistances 11 and 12 of Fig. 2 correspond to the similarly designated resistances of Fig. 1; and resistances d_1, b_1, b_2 , correspond to the similarly designated resistances of Fig. 1. For simplicity, Fig. 2 shows no resistances corresponding to resistances b_3 and d_3 , of Fig. 1, since Fig. 2 is not necessarily intended as indicating 2, 3 as compensating for changes in filament heating current. Tubes 1 and 2, in Fig. 2, are preferably similar and equal in their structure and characteristics. The input circuit of tube 1 includes a secondary winding 41₁ of a transformer 41, the primary winding 41₂ of which is included in series with the source variations O. The input circuit of tube 2 includes the secondary winding 41₃ of the transformer 41. In series with the winding 41₁ is included a secondary winding of a transformer 44₁, and in series with the winding 41₃ is included a secondary winding of a transformer 44₂. The transformer 41₁ has a primary winding in series with a primary winding of the transformer 44₂, in an incoming circuit 42 leading to a source of low frequency signal current such, for example, as a telephone transmitter (not shown). Direct current biasing potential is supplied by battery 20 to the grid of the tube 1 from the junction of resistances d_1 and b_1 , through winding 41₁, and the secondary winding of transformer 44₁. Similarly, biasing potential for the grid of tube 2 is supplied by battery 20 to the grid of tube 2 from the junction of resistances d_2 and b_2 , through the winding 41₃, and the secondary winding of transformer 44₂. A condenser 60 furnishes a low impedance path for current variations from source O between the winding 41₁ and the filament of tube 1. Similarly, a condenser 61 furnishes a low impedance path for the current variations 130

from source O between winding 41₃ and the filament of tube 2. The condensers 60 and 61 in series furnish a low impedance path for the low frequency signaling currents from circuit 42 between windings 41₁ and 41₃.

The output circuits of tubes 1 and 2 are connected in parallel with respect to the battery 5 which is arranged in a common conductor of said circuits. The output circuit of tube 1 includes a primary winding 46 of a transformer 48₁, and the output circuit of tube 2 contains a primary winding 47 of a transformer 48₂. The secondary windings of transformers 48₁ and 48₂ are connected, in series, to an outgoing circuit 50. Lead 70 shown in dotted lines is to indicate that the battery 5 may supply plate current to other circuits, for instance, like that of Fig. 2. Similarly, leads 71 and 72 are to indicate that the battery 10 may supply filament heating current to other circuits such for instance, as that of Fig. 2. Also, the lead 74, and the leads 73 and 73' are to indicate that the battery 20 may supply voltage to other grid biasing circuits, for example, like those of Fig. 2.

Normally, when no currents are impressed upon circuit 42, the high frequency oscillations from source O acting through transformer 41 impress equal voltage variations of the same phase upon the grids of tubes 1 and 2, thereby producing equal fluctuations of the same phase in the output circuits. The windings of transformers 48₁ and 48₂ are so arranged that circuit 50 is differentially coupled to the two output circuits, the fluctuations in the output circuits neutralizing each other with regard to their effects upon the outgoing circuit 50. When low frequency current variations from circuit 42 are impressed upon the repeater circuit through transformers 44₁ and 44₂, the high frequency potential variations are augmented upon one grid and decreased upon the other, producing correspondingly augmented fluctuations in the one output circuit and correspondingly reduced fluctuations in the other. The fluctuations in the output circuits are no longer balanced, and consequently oscillations are produced in the output circuit 50 which have an amplitude proportionate to the instantaneous value of the low frequency modulating currents coming from circuit 42. It is therefore seen that carrier waves are suppressed except when signaling currents are applied.

As pointed out in Blattner Patent 1,483,273, February 12, 1924, in a push-pull amplifier, the tubes of which have their filaments heated from a common source of voltage, each of the tubes tends to prevent voltage variations of the output current of the other tube, due to variations of the voltage

of the heating source, from causing current variations in the outgoing circuit connected to the amplifier, for, as noted in the Blattner patent, at any instant when the heating currents would tend to increase the average difference of potential between the cathode and the grid or the anode of one of the tubes, the heating current would tend to increase the average difference of potential between the cathode and the grid or the anode of the other tube. This mutual compensating action occurs whether or not the grid and plate of each tube is connected to an intermediate point on an impedance across the filament as in Heising Patent 1,432,022, October 17, 1922. However, as pointed out above, where the filaments of the push-pull amplifier tubes are in series and the tubes are supplied from common sources of grid and plate potentials, the effect of voltage variations in the cathode heating source is greater upon the plate or grid potentials of one of the tubes than upon the plate or grid potentials of the other tube, and consequently it is likely to unbalance the tubes and cause undesired current variations in the outgoing circuit connected to the push-pull amplifier, unless some preventative means is employed. By compensating the tubes 1 and 2 of Fig. 2 for changes of filament battery voltage, as the tubes 1 and 2 of Fig. 1 are compensated, each of the tubes 1 and 2 of Fig. 2 has its output current maintained constant, its grid potential variations due to changes of its cathode voltage just counter-acting the effect of its plate potential variations due to the same cause; or if desired, the grid potentials of each of the tubes may be maintained constant in the manner explained above in connection with the description of the operation of tubes 1 and 2 in Fig. 1.

In the circuit of Fig. 2, constant direct current in the output circuit of each of the tubes 1 and 2 results in preventing carrier current from appearing in the outgoing circuit 50 connected to the tubes (or, in other words, prevents carrier leak), and also maintains constant gain of the push-pull amplifier under changing filament battery voltage, and further reduces noise currents, which variations of filament battery voltage tend to create.

The principles of the invention claimed may be embodied in many organizations differing widely from those specifically illustrated and described.

What is claimed is:

1. An energy translating system comprising an electric discharge device having an anode, a cathode, and means for controlling current flow between said anode and cathode, voltage supply means for energizing said cathode, a generator of electromotive force

- for supplying voltage across said anode and cathode, a generator of electromotive force for supplying voltage to said control means, two direct current paths connecting said last 65 generator to points of different potential on said cathode energizing means, and means connecting said control means to a point of one of said paths at a potential different from the potentials of the ends of said one 70 path.
5. An energy translating system comprising an electric discharge device having an anode, a cathode, and a control electrode for controlling current flow between said anode and cathode, voltage supply means for energizing said cathode, said means having thereon two points of different potential, a generator of electromotive force for supplying voltage across said anode and cathode, a generator of electromotive force for supplying biasing potential to said control electrode, said biasing generator having thereon two points of different potential, means connecting one of said points on said biasing generator to one of said points on said cathode energizing means, a resistance connecting said other point on said biasing generator to said other point on said cathode energizing means, and a connection from said control electrode to such a point on said resistance as to compensate for the effect of variations of voltage of said cathode energizing means upon the value of said current between said cathode and said anode. 75 80 85 90
2. An energy translating system comprising an electric discharge device having an anode, a cathode, and a control electrode for controlling current flow between said anode and cathode, voltage supply means for energizing said cathode, said means having thereon two points of different potential, a generator of electromotive force for supplying voltage across said anode and cathode, a generator of electromotive force for supplying biasing potential to said control electrode, said biasing generator having thereon two points of different potential, means connecting one of said points on said biasing generator to one of said points on said cathode energizing means, a resistance connecting said other point on said biasing generator to said other point on said cathode energizing means, and a connection from said control electrode to such a point on said resistance as to compensate for the effect of variations of voltage of said cathode energizing means upon the value of said current between said cathode and said anode. 95
3. An energy translating system comprising an electric discharge device having an anode, a cathode, and a control electrode for controlling current flow between said anode and cathode, voltage supply means for energizing said cathode, said means having thereon two points of different potential, a generator of electromotive force for supplying voltage across said anode and cathode, a generator of electromotive force for supplying biasing potential to said control electrode, said biasing generator having thereon two points of different potential, means connecting one of said points on said biasing generator to one of said points on said cathode energizing means, a resistance connecting said other point on said biasing generator to said other point on said cathode energizing means, and a connection from said control electrode to such a point on said resistance as to compensate for the effect of variations of voltage of said cathode energizing means upon the value of said current between said cathode and said anode. 100 105 110
4. An energy translating system comprising an electric discharge device having an anode, a cathode, and a control electrode for controlling current flow between said anode and cathode, voltage supply means for energizing said cathode, said means having thereon two points of different potential, a generator of electromotive force for supplying voltage across said anode and cathode, a generator of electromotive force for supplying biasing potential to said control electrode, said biasing generator having thereon two points of different potential, means connecting one of said points on said biasing generator to one of said points on said cathode energizing means, a resistance connecting said other point on said biasing generator to said other point on said cathode energizing means, and a connection from said control electrode to such a point on said resistance as to compensate for the effect of variations of voltage of said cathode energizing means upon the value of said current between said cathode and said anode. 115
5. An energy translating system comprising an electron discharge tube having an anode, a cathode, and a control electrode for controlling current flow between said anode and cathode, voltage supply means for energizing said cathode, said means having thereon a point of one potential and a point of lower potential, a generator of electromotive force for supplying voltage across said anode and cathode, a generator of electromotive force for supplying biasing potential to said control electrode, said biasing generator having thereon two points of different potential, means comprising a resistance connecting the more negative of said last two points to the more negative of said first two points, means connecting the remaining two of said four points, and a connection from said control electrode to such a point on said resistance as to compensate for the effect of variations of voltage of said cathode energizing means upon the potential of said control electrode. 120 125

- connecting the more negative of said last two points to the more negative of said first two points, means connecting together the remaining two of said four points and said 5 generator for supplying voltage across said anode and cathode, and a connection from said control electrode to such a point between the ends of said resistance as to compensate for the effect of variations of voltage 10 of said cathode energizing means upon the potential of said control electrode.
8. An energy translating system comprising an electron tube having an anode, a cathode and a control electrode for controlling current flow between said anode and cathode, a voltage supply source, a circuit connected across said source and including said cathode, a circuit shunted across said first circuit and including an electromotive force 15 generator, and a connection from said control electrode to a point on said second circuit.
9. An energy translating system comprising a plurality of electron tubes each having an anode, a cathode, and a control electrode, means connecting said cathodes in series with each other, means for energizing said series connected cathodes, said energizing means being thereon points of different 20 potential, electromotive force generating means for supplying biasing potentials to said control electrodes, said biasing generating means having thereon points of different potentials one of which is connected to one 25 of said points on said cathode energizing means, resistances respectively connecting said other points on said biasing generating means to said other points on said cathode energizing means, and connections from each 30 of said control electrodes to a point between the ends of one of said resistances, respectively.
10. An energy translating system comprising a plurality of electron tubes each having 45 an anode, a cathode, and a control electrode, means connecting said cathodes in series with each other, means for energizing said series connected cathodes, said energizing means having thereon points of different potential, electromotive force generating means 50 for supplying voltage across said anodes and cathodes, common electromotive force generating means for supplying biasing potentials to said control electrodes, said biasing 55 generating means having thereon points of different potentials one of which is connected to highest potential one of said points on said cathode energizing means and to said means for supplying voltage across said 60 anodes and cathodes, resistances respectively connecting said other points on said cathode energizing means, and connections from each of said control electrodes to such a point between the ends of one of said resistances, re-
- spectively, as to compensate for effects of 65 variations of voltage of said cathode energizing means upon the operation of the system.
11. An energy translating system comprising an incoming circuit, an outgoing circuit, 70 electric discharge apparatus connected between said circuits, said apparatus including a pair of cathodes and also including a pair of input circuits and a pair of output circuits, each of said input circuits and output circuits including one of said cathodes, the two circuits of one of said pairs being oppositely associated with one of said first two circuits, and at least one of the 75 circuits of the other of said pairs being associated with the other of said first two circuits, means for energizing said cathodes in such manner that changes in the characteristics of said means tend to effect the currents in said two output circuits in different degree, and means for counteracting 80 said tendency.
12. In combination, two discharge devices, each having an anode and an electron emitting cathode for permitting space discharge 90 current to flow through said device, means supplying current of varying amplitude for rendering said cathodes active to emit electrons, means actuated in response to variations of said space discharge currents, the 95 variations of said current from said first means tending to produce two opposing but unequal effects upon said means, and means for substantially equalizing said last effects.
13. A translating apparatus comprising a 100 pair of repeater circuits, two separate sources of current variations, said repeater circuits being symmetrically associated with one of said sources and being oppositely associated with the other source, an outgoing circuit associated with said repeater circuits, means for energizing each of said repeaters and subject to changes which tend to simultaneously produce two opposite but unequal effects upon the control of one of 105 said sources over said outgoing circuit, and means for equalizing said effects.
14. A modulating system comprising a 110 pair of translating devices, a source of high frequency energy similarly connected with said devices, a source of modulating energy oppositely connected with said devices, an outgoing circuit differentially connected with said devices, means for energizing each 115 of said devices and subject to change which tend to simultaneously produce two opposite but unequal effects upon the control of said high frequency source over said outgoing circuit, and means for equalizing said effects.
15. A modulating system comprising a 120 pair of translating devices each including a cathode, a source of high frequency energy 125

- similarly connected to said devices and including a cathode, a source of modulating energy oppositely connected with said devices, an outgoing circuit differentially connected with said devices, means energizing all of said cathodes in series with each other and subject to changes which tend to simultaneously produce two opposite but unequal effects upon the control of said high frequency source over said outgoing circuit, 10 and means for equalizing said effects.
5. In witness whereof, I hereunto subscribe my name this 17th day of April, A. D. 1924.

HUGH R. ROBINSON.
